UNITED STATES PATENT OFFICE.

KNUD KNUDSEN, OF DANBURY, CONNECTICUT.

ELECTRICAL CONNECTING DEVICE.

Application filed March 14, 1922. Serial No. 543,719.

To all whom it may concern:

Be it known that I, KNUD KNUDSEN, a subject of the King of Denmark, and a resident of Danbury, in the county of Fairfield and State of Connecticut, have invented an Improvement in Electrical Connecting Devices, of which the following is a specification.

This invention relates to electrical connecting devices, and with regard to the more specific features thereof, to the construction of devices of this sort of the so-called "push button" type. One of the objects thereof is to provide devices of the above nature of simple and practical construction and of efficient action. Another object is to provide a device of the above nature which can be quickly and conveniently taken apart and reassembled, and yet the parts of which are securely held in assembled relation. Another object is to provide a push button of inexpensive construction and yet well adapted to meet the conditions of hard practical use. Other objects will be in part obvious and in part pointed out hereinafter.

The invention accordingly consists in the features of construction, combinations of elements and arrangement of parts, all of which will be exemplified in the construction hereinafter described, and the scope of the application of which will be indicated in the following claims.

In the accompanying drawing in which is illustrated one of various possible embodiments of this invention,

Figure 1 is a sectional view taken of the line 1—1 of Figure 2;

Figure 2 is a bottom plan view of the device shown in Figure 1.

Similar reference characters refer to similar parts throughout both views of the drawing.

Referring now in detail to Figure 1 of the drawing, there is shown a plate or bar 10 of insulating material, having threaded thereinto from the bottom, screws 11 and 12, the ends of which are rounded as shown at 13, in order to form contact points. Leading to these screws is a pair of electrical conductors 14 and 15 between which it is desired to make and break an electrical connection.

The part 10 is rounded at its ends in grooves concentric to the central axis of the device, and these ends rest within recesses formed by the flanges 16 and depressions 17

in the ends of a sheet metal supporting member 18. These recesses are curved in plan to conform with the curved ends of the plate 10, and thus permit a relative rotary motion of these parts about a vertical axis in a counter-clockwise direction having reference to Figure 2 of the drawings. Rotation in the opposite direction is prevented by the stop shoulders 19 stamped at the ends 65 of the recess in the part 18.

At the upper end of the support 18, it is provided with a round central opening, the edges 20 of which rest within a flange 21, turned over in the central opening of an outer casing 22. This construction interlocks the bridging or supporting member 18 to the casing, and it may be more firmly secured thereto, if desired, by sweating or spot-welding at the surfaces 23.

The casing 22 extends downwardly to enclose the parts above described, and thence outwardly to provide an annular portion 24, the edges of which are flanged as at 25, to rest against the wall or supporting surface 26.

Mounted upon the insulating plate 10 is a flat spring 28, which at its stationary end passes downwardly through the opening 29 and thence back upon itself through the opening 30, and is provided with a bent end 31 resting against the upper surface of the part 10 and abutting against screw 12. The resilience of this spring member locks it firmly into assembled relation with respect to the plate 10, and yet due partially to the size of the opening 29, its free end is permitted an unimpeded swing. Normally this free end of the spring occupies the position indicated in dotted lines at 32, and the push button 33 is correspondingly elevated. This push button however, which is provided with the flange 34 to limit its upward movement, is here shown in operative position, namely, depressed to force the spring member 28 into firm contact with the upper ends of the screws 11 and 12. In this position, the latter screws are electrically bridged, and it may be noted that due to the construction of the spring, there is a slight rubbing movement as the button is depressed, which tends to maintain the contacting surfaces clean and in condition to make a low resistance engagement.

Considering now the action of the device:—With the plate 10 having its ends resting in the recesses in support 18 and

2
 against stop shoulders 19, the conductors 14 and 15 are drawn from the wall to such extent as to permit their bare ends to be secured beneath the heads of the screws 11 and 12. This connection of the wires may be made without taking the device apart. The entire device may then be secured to the wall by the screws 27, which are spaced from and entirely independent of the conductors of the casing, thus permitting them to engage the wall at a firm portion distant from the opening through which the wires are drawn; also this spacing of the screws obviates the chance of their contact with the wires, with the likelihood of short-circuiting or grounding the latter. If it be desired to disassemble the device for purposes of inspection or repair, the screws 27 are removed without altering the unitary character of the construction. The wires then may be drawn to a safe distance through the wall, and thereupon the plate 10 which contains the entire electrical equipment, may be quickly removed by twisting it with respect to the support 18. Due to the extremely small number of parts and the direct electrical circuit, there is small likelihood of the device becoming inoperative, and in case of breakage, any of the parts may be quickly replaced at low cost.

It will thus be seen that there is provided a construction in which the several objects of this invention are achieved.

As various changes might be made in the above construction without departing from the scope of this invention, it is to be understood that all matter herein described, or shown in the accompanying drawings, is to be interpreted as illustrative and not in a limiting sense.

I claim as my invention:

1. In construction for push buttons and the like, in combination, a member of insulating material, a flat spring passing through said member and shaped to interlock therewith, and contact means mounted upon said member with which said spring co-acts to form an electrical connection.
2. In construction for push buttons and the like, in combination, a member formed of insulating material, a pair of screws passing through said member, a pair of conductors having their ends respectively secured to the outer ends of said screws, and a spring member interlocked with said first member and shaped to co-act with the inner ends of said screws and form an electrical connection therebetween.
3. In construction for push buttons and the like, in combination, a casing member, an inner member rigidly secured to said casing and extending across the same and having its ends shaped to form a pair of inwardly facing recesses, and an inner device to which the conductors are secured, pro-

vided with ends adapted to be rotated into interlocked relation with said recesses.

4. In construction for push buttons and the like, in combination, an insulating member, a pair of members passing therethrough and adapted to have removably connected to their outer ends a pair of conductors, a spring mounted upon said insulating member and adapted upon being depressed, to complete an electric circuit between said members, said spring being mounted to move into and out of engagement with the inner end of one of said members, an outer casing provided with means carried interiorly thereof, said means having a pair of spaced recesses with which said insulating member may be interlocked upon movement of said insulating member in its own plane and relative to said means, and means adapted to secure the said outer casing to the wall.

5. In construction for push buttons and the like, in combination, a member formed of insulating material, a pair of terminal members thereon, and a spring member interlocked with said insulating member and adapted to bridge across said two terminal members.

6. In construction for push buttons and the like, in combination, a member formed of insulating material and providing a substantially flat upper surface; a terminal thereon and projecting upwardly from said substantially flat surface of said member; and a flat spring bent substantially upon itself to provide an elongated operative portion extending over the substantially flat upper surface of said member for coaction with said terminal, an end portion seated upon the flat upper surface of said member, and an intervening looped portion extending below the plane of said flat upper surface of said member.

7. In construction for push buttons and the like, in combination, a supporting block formed of insulating material; a flat spring mounted upon said block, said spring having an end portion resting against an upper part of said block and adjacent one end thereof, a substantially loop-shaped portion extending from said end portion downwardly below the plane of the upper part of said block and thence upwardly, said spring being thereupon extended into an operative portion overlapping but spaced from the upper part of said block; and contact means upon said member with which may coact to form an electrical connection.

8. In construction for push buttons and the like, in combination, a supporting block formed of insulating material and having a portion cut away at one end; a screw passing through said block and adapted to permit connection thereto of a conductor; a flat spring bent substantially upon itself to

- provide an end portion resting against an upper part of said supporting block, an operative end portion for contact-making coaction with said screw, and an intervening substantially loop-shaped intermediate portion extending below the plane of the upper part of said block and accommodated in said cut-away portion at one end of said block.
10. In construction for push buttons and the like, in combination, a member formed of insulating material; a flat spring associated therewith and passing twice through said member, and having a portion overlapping said member; and contact means mounted upon said member and adapted to coact with said overlapping portion of said spring to form an electrical connection.
10. In construction for push buttons and the like, in combination, an insulating supporting block having a pair of spaced screws passing therethrough and having an aperture adjacent one of said screws; and a spring member having an end portion resting against an upper part of said block, said member being shaped to pass downwardly through said aperture, thence upwardly to form an operative end portion overlapping said block for coaction with one of said screws, said block being cut away to permit the upwardly extending portion of said spring to pass into overlapping relation relative to said block and one of said screws.
15. 11. In construction for push buttons and the like, in combination, a casing adapted to rest against the surface of a wall; an insulating block having mounted thereon a projecting contact member; means mounting said insulating block within said casing but spaced from the plane of the surface of said wall and with said contact member extending inwardly with respect to said casing; and a spring member associated with said insulating block for coaction with said contact member, said spring member being shaped to provide a free operative end portion overlapping the inner face of said block and also said contact member, and a looped portion extending into the space between the outer face of said block and the plane of the surface of said wall.
12. In construction for push buttons and the like, in combination, a casing; an insulating block having mounted thereon a projecting contact member; means mounting said insulating block within said casing and with said contact member extending inwardly with respect to said casing; and a spring for coaction with said contact member having an end portion relatively fixed with respect to said insulating block, said spring being shaped to provide a free operative end overlapping the inner face of said block for coaction with said contact mem-
- ber and a substantially loop-shaped portion extending outwardly with respect to said casing and beyond the plane of the inner face of said insulating block.
13. In construction for push buttons and the like, in combination, a casing, an inner member secured to said casing and extending transversely thereof, an insulating block carrying a terminal member and a spring member for coaction therewith, said spring member being interlocked with said insulating block, and means for removably interlocking said insulating block with said inner member.
14. In construction for push buttons and the like, in combination, a sheet-metal supporting member having downwardly extending and laterally spaced portions of arcuate shape, an inner device carrying connecting mechanism and provided with end portions of arcuate shape adapted to be fitted between said spaced portions of said supporting member, means independent of said inner device for mounting said supporting member on a wall, and a shoulder in each of said spaced arcuate portions of said sheet-metal member pressed inwardly toward said arcuate end portions of said second member for limiting relative rotational movement between said two members.
15. In construction for push buttons and the like, in combination, a casing; a plate-like substantially rectangularly shaped insulating member having a pair of screws threaded therethrough and from the outer face thereof, said screws being adapted to have removably connected to their outer ends a pair of conductors; means associated with said casing and providing a supporting ledge adjacent the lower end of said casing, said ledge having an interruption therein to permit the insertion therethrough and into said casing of said plate-like member and to permit, upon a subsequent rotary movement of said plate-like member to swing an end portion of the latter onto said supporting ledge; and contact-making mechanism interposed between the upper end of said casing and said plate member for coaction with the inner end of one of said screws.
16. In construction for push buttons and the like, in combination, a casing; a plate-like insulating member of substantially rectangular shape having a pair of screws threaded therethrough and from the outer face thereof, said screws being adapted to have removably connected to their outer ends a pair of conductors; and a sheet-metal supporting member extending transversely of said casing and secured thereto, said supporting member being arranged to support said insulating member substantially intermediate the upper and lower ends of said casing and having a pair of spaced depending portions between and by which two op-

posite ends of said rectangularly shaped insulating member are engaged and held.

17. In construction for push buttons and the like, in combination, a casing; a plate-like insulating member of substantially rectangular shape having a pair of screws threaded therethrough and from the outer face thereof, said screws being adapted to have removably connected to their outer ends a pair of conductors; a sheet-metal supporting member extending transversely of said casing and secured thereto, said supporting member being arranged to support said insulating member substantially inter-

mediate the upper and lower ends of said casing and having a pair of spaced depending portions between and by which two opposite ends of said rectangularly shaped insulating member are engaged and held; and a spring bent to form an operative portion overlapping one of said screws and an intermediate substantially loop-shaped portion passing twice through the plane of one face of said insulating member.

In testimony whereof, I have signed my name to this specification this 21st day of February, 1922.

KNUD KNUDSEN.

posite ends of said rectangularly shaped insulating member are engaged and held.

17. In construction for push buttons and the like, in combination, a casing; a plate-like insulating member of substantially rectangular shape having a pair of screws threaded therethrough and from the outer face thereof, said screws being adapted to have removably connected to their outer ends a pair of conductors; a sheet-metal supporting member extending transversely of said casing and secured thereto, said supporting member being arranged to support said insulating member substantially inter-

mediate the upper and lower ends of said 15 casing and having a pair of spaced depending portions between and by which two opposite ends of said rectangularly shaped insulating member are engaged and held; and a spring bent to form an operative portion 20 overlapping one of said screws and an intermediate substantially loop-shaped portion passing twice through the plane of one face of said insulating member.

In testimony whereof, I have signed my 25 name to this specification this 21st day of February, 1922.

KNUD KNUDSEN.

Certificate of Correction.

It is hereby certified that in Letters Patent No. 1,528,491, granted March 3, 1925, upon the application of Knud Knudsen, of Danbury, Connecticut, for an improvement in "Electrical Connecting Devices," an error appears in the printed specification requiring correction as follows: Page 4, after line 24, insert the following as claims 18 and 19.

18. In construction for push buttons and the like, in combination, a casing adapted to rest against the surface of a wall and having a push button movably supported at its upper end; an insulating block having mounted thereon a contact member; means mounting said insulating block within said casing but spaced from the plane of the surface of said wall; and a spring for coaction with said contact member, said spring being interlocked at one end thereof with said insulating block and having an operative yieldable portion extending from the underside of said insulating block into the space between said insulating block and the upper portion of said casing for coaction with said push button.

19. In construction for push buttons and the like, in combination, a casing, an inner member of sheet metal secured to said casing and extending across the casing, an insulating block carrying a terminal member and a spring member for coaction therewith, said spring member being interlocked at one end thereof with said insulating block, and said sheet metal inner member and said block being shaped to permit the latter to be seated within the former upon relative movement therebetween;

and that the said Letters Patent should be read with this correction therein that the same may conform to the record of the case in the Patent Office.

Signed and sealed this 24th day of March, A. D. 1925.

KARL FENNING,
Acting Commissioner of Patents.

Certificate of Correction.

It is hereby certified that in Letters Patent No. 1,528,491, granted March 3, 1925, upon the application of Knud Knudsen, of Danbury, Connecticut, for an improvement in "Electrical Connecting Devices," an error appears in the printed specification requiring correction as follows: Page 4, after line 24, insert the following as claims 18 and 19.

18. In construction for push buttons and the like, in combination, a casing adapted to rest against the surface of a wall and having a push button movably supported at its upper end; an insulating block having mounted thereon a contact member; means mounting said insulating block within said casing but spaced from the plane of the surface of said wall; and a spring for coaction with said contact member, said spring being interlocked at one end thereof with said insulating block and having an operative yieldable portion extending from the underside of said insulating block into the space between said insulating block and the upper portion of said casing for coaction with said push button.

19. In construction for push buttons and the like, in combination, a casing, an inner member of sheet metal secured to said casing and extending across the casing, an insulating block carrying a terminal member and a spring member for coaction therewith, said spring member being interlocked at one end thereof with said insulating block, and said sheet metal inner member and said block being shaped to permit the latter to be seated within the former upon relative movement therebetween;

and that the said Letters Patent should be read with this correction therein that the same may conform to the record of the case in the Patent Office.

Signed and sealed this 24th day of March, A. D. 1925.
